[57] CLAIM

The ornamental design for a single sample processor syringe for solid phase extraction tubes, as shown and described.

DESCRIPTION

FIG. 1 is a front elevational view of a single sample processor syringe for solid phase extraction tubes, showing our new design;

FIG. 2 is a top plan view thereof;

FIG. 3 is a bottom plan view thereof;

FIG. 4 is a side elevational view thereof, the opposite

side elevational view being identical thereto;

FIG. 5 is a rear elevational view thereof;

FIG. 6 is a perspective view thereof.

FIG. 1

FIG. 2

FIG. 3

FIG. 4

FIG. 5

FIG. 6
